(57) **CLAIM**

The ornamental design for a therapeutic compression wrap as shown and described.

DESCRIPTION

FIG. 1 is a perspective view of our new design;
FIG. 2 is an elevation view of the front side of the design of FIG. 1;
FIG. 3 is an elevation view of the back side of the design of FIG. 1;
FIG. 4 is an elevation view of the right side of the design of FIG. 1;
FIG. 5 is an elevation view of the top side of the design of FIG. 1;
FIG. 6 is an elevation view of the bottom side of the design of FIG. 1;
FIG. 7 is an elevation view of the left side of the design of FIG. 1; and,
FIGS. 8 and 9 are exemplary frontal views of the article of the design as applied to a human joint in two alternative positions.

The broken lines shown in the figures illustrate portions of the therapeutic compression wrap that form no part of the claimed design. The additional broken lines in FIGS. 8 and 9 illustrate environment and form no part of the claimed design.
